UNITED STATES PATENT OFFICE.

WILLIAM ENSSLER, OF ROCHESTER, NEW YORK.

ATTACHMENT FOR LADDERS.

Application filed June 17, 1924. Serial No. 720,706.

To all whom it may concern:

Be it known that I, WILLIAM ENSSLER, a citizen of the Republic of Germany, residing at Rochester, in the county of Monroe and 5 State of New York, have invented certain new and useful Improvements in Attachments for Ladders, of which the following is a specification.

The object of this invention is to provide 10 a new and improved attachment for a ladder with which the upper end thereof may be securely anchored to prevent its sliding or shifting after the ladder has been located in the desired position.

15 This and other objects of this invention will be fully illustrated in the drawings, described in the specification and pointed out in the claims at the end thereof.

In the accompanying drawings:

20 Figure 1 is a top plan view of the attachment as it appears when mounted on the upper end of a ladder.

Figure 2 is a side elevation of the attachment and the upper end of the ladder to 25 which it is attached.

Figure 3 is a top plan view of a modified form of the attachment.

In the several figures of the drawings like reference numerals indicate like parts.

30 After a ladder is properly located there is always the danger of having the upper end thereof slide to one side or the other unless some means are provided that anchors the upper end of the ladder and prevents 35 its shifting when the workman climbs up on the ladder. Such attachments are not new but the attachment forming the subject matter of this invention is so constructed that it can be readily adjusted at any time 40 either from the ground or from the ladder while older devices of this nature have to be adjusted before the ladder is put in place.

45 As illustrated in the figures the attachment comprises a pair of short rectangular sleeves 1 and 2 that are adapted to slide over the upper ends of the ladder rails and are clamped thereto by means of the clamping screws 3, 3. Each of the sleeves 1 and 2 has a rearwardly extending bracket 4 integral therewith. On these brackets are provided the horizontal bearings 5, 5 in which the shafts 6 and 7 respectively are mounted to rotate. Each of these shafts carries at its outer end a worm 8. These 55 worms mesh with the worm wheels 9, 9 carried on the inner ends of the anchoring

arms 10, 10 and are pivoted on the pivot pins 11, 11 mounted in the rearwardly extending brackets of the sleeves 1 and 2. The pivot pins comprise shouldered machine 60 screws that are threaded into the brackets forming a rigid bearing pin for the worm wheels to rotate thereon.

A collar 11^A is keyed to each of the shafts 6 and 7 on the outside of the horizontal 65 bearings and keeps the shafts from sliding therein. The inner ends of the shafts extend into the hollow shaft 12 and are adjustably keyed therein by means of the set screws 13 and 14. The hollow shaft 12 carries the 70 double grooved pulley 15 in the middle thereof over which the ropes or cables 16 and 17 are adapted to pass. The ropes are wound around the pulley in their respective grooves so that by pulling on one of 75 the ropes the pulley is rotated in one direction and by pulling the other rope the pulley is rotated in the opposite direction. The worms 8, 8 can thus be rotated to turn the arms 10, 10 either in or out by rotating the 80 pulley as above described. In this way the arms may be adjusted so as to properly anchor the upper end of the ladder and hold it against sliding on the object against which it is placed. If this should be a pole 85 or narrow object the arms are placed so as to partly embrace it, otherwise the arms are positioned to allow the pointed ends thereof to dig into the object against which it is placed. In cases where it is objectionable to have the points on the ends dig 90 into the object against which the ladder is placed, pads made of rubber or other suitable material may be slipped over the points so that they will rest against the object and prevent the upper end of the ladder from 95 sliding thru the frictional contact between these pads and the object that they engage.

In Figure 3 is illustrated a modification of the attachment which differs from the 100 attachment illustrated in Figures 1 and 2 in that each of the anchoring arms is made adjustable individually. For this purpose the sleeves 20 and 21 that are separately clamped to the upper ends of the ladder by means of the clamping screws 22 are provided with sidewardly projecting brackets 105 that carry the horizontal bearings 23, 23 and the pivot pins 24, 24. A shaft 25 carrying a worm 26^A and a worm wheel 27 is mounted 110 in each of the horizontal bearings and on the pivot pins, respectively. Each shaft 25 has

a double grooved pulley 26 keyed thereon over which two ropes or cables can pass. The pulleys can thus be individually rotated in either one or the other direction in order 5 to swing the arms controlled by these pulleys in the desired direction and place them properly against the object on which the upper end of the ladder is to rest.

By making the ends of the shafts 6 and 7 10 adjustable in and out of the hollow shaft 12 on the attachment illustrated in Figures 1 and 2 the attachment may be attached to ladders of different widths. Thus for a ladder of small width the shafts 6 and 7 are 15 inserted into the hollow shaft the full length thereof while for a ladder of greater width these shafts are moved out of the hollow shaft in order to bridge the longer distance between the upper ends of the ladder.

20 I claim:

1. In an attachment for ladders, the combination of a pair of sleeves adapted to telescope over the ends of the uprights of a ladder, a bracket formed on each of said 25 sleeves, a worm mounted to rotate on said bracket, a pivot pin carried on said bracket, a worm wheel mounted to rotate on said pivot pin and adapted to mesh with said worm, an arm projecting from said worm 30 wheel, and means for rotating said worm in either one or the other direction.

2. In an attachment for ladders, the combination of a pair of sleeves adapted to telescope over the ends of the uprights of a 35 ladder, means for clamping said sleeves to the ladder, a bracket projecting from each of said sleeves, a horizontal bearing formed on each of said brackets, said bearings being in line with each other, a short shaft 40 mounted to rotate in each of said bearings, a hollow shaft telescoping over the ends of said short shafts, a pulley carried by said hollow shaft, a worm carried by each of said short shafts, a worm wheel mounted to rotate 45 adjacent to each of said worms and

meshing therewith, an arm carried by each of said worm wheels, said arms being adapted to simultaneously swing in either one or the other direction on the rotation of said pulley.

3. In an attachment for ladders, the combination of a pair of sleeves adapted to telescope over the ends of the uprights of a ladder, means for clamping said sleeves to the ladder, a bracket projecting from each of said sleeves, a horizontal bearing formed on each of said brackets, said bearings being in line with each other, a short shaft mounted to rotate in each of said bearings, a hollow shaft telescoping over the ends of said short shafts, a pulley carried by said hollow shaft, a worm carried by each of said short shafts, a worm wheel mounted to rotate adjacent to each of said worms and meshing therewith, an arm carried by each of said worm wheels, said arms being adapted to simultaneously swing in either one or the other direction on the rotation of said pulley, said short shafts being adjustable in and out of said hollow shaft to increase 60 or decrease the distance between said pair of sleeves corresponding to the distance between the uprights of the ladder to which said sleeves are to be clamped.

4. In an attachment for ladders, the combination of a pair of sleeves adapted to telescope over the ends of the uprights of a ladder, a bracket formed on each of said sleeves, a worm mounted to rotate on said bracket, a pivot pin carried on said bracket, 75 a worm wheel mounted to rotate on said pivot pin and adapted to mesh with said worm, an arm projecting from said worm wheel, and means for rotating said worm in either one or the other direction, said arms being 80 curved inwardly and adapted to embrace a narrow object to securely hold the upper end of the ladder in place thereon.

In testimony whereof I affix my signature,
WILLIAM ENSSLE
